UNITED STATES PATENT OFFICE.

JAKOB E. NOEGGERATH, OF SCHENECTADY, NEW YORK, ASSIGNOR TO GENERAL ELECTRIC COMPANY, A CORPORATION OF NEW YORK.

CURRENT-COLLECTING APPARATUS FOR DYNAMO-ELECTRIC MACHINES.

No. 904,801.

Specification of Letters Patent.

Patented Nov. 24, 1908.

Application filed October 10, 1906. Serial No. 338,257.

To all whom it may concern:

Be it known that I, JAKOB E. NOEGGERATH, a citizen of the United States, residing at Schenectady, county of Schenectady, State of New York, have invented certain new and useful Improvements in Current-Collecting Apparatus for Dynamo-Electric Machines, of which the following is a specification.

My invention relates to dynamo-electric machines and more particularly to brushes and supports therefor, and has for its object to improve the same.

The various features of my invention will be pointed out with particularity in the appended claims; but for a full understanding of my invention and of its objects and advantages, reference may be had to the following detailed description taken in connection with the accompanying drawing.

In said drawing, Figure 1 is a side elevation of a brush and brush-holder arranged in accordance with the present invention, the brush bearing upon a collector ring; Fig. 2 is a plan view of the parts shown in Fig. 1, a portion of the brush-holder stud broken away to more clearly show its construction; and Fig. 3 is an enlarged longitudinal section of one end of the brush.

In dynamo-electric machines having current collectors which run at high peripheral speeds the brushes wear away rapidly, and in high speed unipolar machines, whose collector rings have peripheral speeds much higher than in other types of machines, the wearing of the brushes presents a serious problem. In one of its aspects my invention relates to means for overcoming this objectionable wear upon brushes.

I have found that there is no appreciable wear in a brush either when there is no current flowing through it, or when there is no relative movement between the brush and the collectors; but when both of these conditions are present, wear takes place, and in increased ratio as either the current or the relative movement increases.

By my invention the brush is so constructed that the portion thereof which takes the wear carries but little current while the portion through which the current flows is subjected to but little wearing influence. This may conveniently be accomplished by building up the brush of strips or laminations, certain of the strips

being composed of a good conducting material, and others having a lower conductivity and preferably a higher mechanical strength. Such a brush is illustrated in the drawing, where A is a brush being made up of thin strips or bundles of strips 1, preferably of copper or bronze, alternating with strips 2, of iron or other material having a considerably lower conductivity than the copper. 3, 3, 3, are stiffening strips which may be added where it is desired to have the brush stiffer than would be the case if the strips 1 and 2 alone were used. 4 is a collector ring upon which the brush bears.

In operation, the current density in the strips 2 is quite low but it is high in the strips 1. Therefore, the tendency of the strips 2 to wear away is small; and, since it is impossible for the copper or bronze strips to wear away at a faster rate, the brush as a whole wears but slowly, even for very high peripheral speeds of the collector ring.

B is a brush-holder which may be advantageously used with brushes of the character described. This brush holder consists of a member 5 adapted to be clamped upon the brush-holder stud 6 in any suitable manner, as by means of a set screw 7 passing through ears 8 and 9 on the member.

10 is the brush receiving member journaled on the brush-holder stud by means of ears 11 and 12 which, when the parts are assembled, are positioned on opposite sides of the member 5. On the member 10 is a brush guide 13 through which the brush 10 passes and in which it is adjustably secured by means of a thumb-screw 14. The brush may be forced against the collector ring with any desired degree of pressure by means of a thumb-screw 15 carried by an arm 16 on the member 10, and bearing at one end upon an arm 17 projecting from the member 5, and therefore fixed with respect to the stud.

18 is a spring arranged on the upper side of the brush and intended particularly to effect the proper pressure between the extreme outer end of the brush and collector ring. This spring may conveniently be substantially U-shaped throughout the major portion of its length, one arm thereof bearing upon the top of the brush, but being preferably bent upward out of engagement with the brush adjacent the outer end thereof, as at 19, and then engaging the brush 110

again at the extreme outer end 20. The end of the other arm of the spring is adapted to bear upon the bow-shaped portion 19 of the companion arm, whereby a stiff spring 5 action is obtained at the extreme outer end of the brush. The tension of the spring may be adjusted by means of wing nuts 21, screw-threaded upon the shaft of the thumb-screw 14, and bearing upon the outer side of 10 the upper arm of the spring. In placing the parts in position, the arm of the spring which bears upon the brush is preferably placed in position in the brush guide 13, together with the brush, so as to be locked in 15 position at the same time, and by the same means as the brush itself. Thus, it will be seen that the brush as a whole may be adjusted so as to vary the pressure between it and the collector ring, and a further independent adjustment at the tip of the brush 20 may be obtained by means of the spring.

The brush holder stud 6 illustrated, is adapted to support two brush holders differing in potential and consists of a member 22 25 having a socket, and a member 23 having a tenon adapted to enter the socket and leave sufficient space for the substantial sleeve of insulation 24 between the two members. By making the tenon sufficiently long, a very 30 rigid two-part stud, the ends of which are effectively insulated from each other, may be obtained.

What I claim as new and desire to secure by Letters Patent of the United States, is, 35

1. In a dynamo-electric machine, a collector ring arranged to operate at a high peripheral speed, and a brush engaging said ring, said brush being composed of stiffening pieces and thin strips of material having high conductivity, alternating with thin strips having low conductivity and greater mechanical strength than the other strips, one of said stiffening pieces being placed on each side of the thin strips.

2. In a dynamo-electric machine, a collector ring arranged to operate at a high 45 peripheral speed, and a brush engaging said ring, said brush being composed of stiffening pieces and thin strips of material having high conductivity, alternating with thin strips having low conductivity and greater mechanical strength than the other strips, one of said stiffening pieces being placed on each side of the thin strips and one stiffening piece substantially in the middle of the 50 thin strips.

3. In a dynamo-electric machine, a current collector, a longitudinally-laminated brush engaging said collector, a brush holder, and a substantially U-shaped spring on said 60 brush holder, one arm of said U bearing upon the top of said brush throughout the major portion of its length and having a bow-shaped portion engaging the brush adjacent the outer end thereof.

4. In a dynamo-electric machine, a current collector, a longitudinally-laminated brush engaging said collector, a brush holder, a substantially U-shaped spring on said 70 holder, one arm of said U bearing upon the top of said brush throughout the major portion of its length, and having a bow-shaped portion engaging the brush adjacent the outer end thereof, the other arm of the U being adapted to bear upon the bow-shaped 75 portion of said first arm, and means for adjusting the tension of said spring.

5. A brush holder stud consisting of a member having a socket, a member having a projection entered into said socket, and in 80 insulation between said members.

In witness whereof, I have hereunto set my hand this 9th day of October, 1906.

JAKOB E. NOEGGERATH.
